PUMP

Ralph R. Boyles and Edward A. Wilhelm, St. Paul, Minn., assignors to Waterous Company, St. Paul, Minn., a corporation of Minnesota

Application July 13, 1938, Serial No. 219,012

7 Claims. (Cl. 103—106)

The present invention relates to pumps of the type that are adapted to be mounted upon a standard automotive truck chassis, to be driven by the automotive engine and used for fire engine service.

The fire underwriters require apparatus of the character to have a wide range of operating pressures and capacities which is fulfilled most readily by pumps of the centrifugal type designed for both series and parallel operation. At the same time the apparatus must be physically adaptable to a wide variety of makes and models of automotive truck chassis and it must be compact and simple in construction for purposes of first cost, subsequent servicing, and ease of operation in the hands of relatively inexperienced mechanics.

It is an object of this invention to provide a pump structure having the aforesaid characteristics.

It is a further object of the invention to provide a pump of the centrifugal type which may be mounted in a variety of positions on a truck chassis of standard construction.

It is a further object of the invention to provide a centrifugal pump mechanism of the multistage type and a cooperating integrally formed transfer valve mechanism by which the pump may be changed from a position in which the pumping stages are operated in parallel with each other to yield a high capacity at relatively low pressure to a position in which the pumping stages are operated in series relation to yield a lower capacity at relatively high pressure.

It is a further object of the invention to provide a multistage pumping mechanism having a plurality of intake passages and a plurality of outlet passages which may be used singly or in unison with each other.

It is a further object of the invention to provide a multistage pump having intake passages for the direct introduction of water to one stage when the stages are operated in series relation and provided with additional passageways and means for the direct introduction of water when the stages are operated in parallel relation.

It is also an object of the invention to provide a simplified centrifugal pump construction of the multistage type having a housing which is composed of only two main portions, and it is a further object of the invention to provide such a pump mechanism including transfer valve means and passageways in only one of said main portions for the ready conversion of said mechanism from a parallel to a series pumping arrangement.

It is a further object of the invention to provide

a centrifugal pump of the fire engine type having widely spaced outlet delivery channels, together with a priming pump of the positive displacement type and automatic valve mechanisms in said widely spaced channels for the automatic priming of said centrifugal pump.

It is a further object of the invention to provide a series-parallel multistage centrifugal pump composed generally of two housings and including an intake passage, one section of said pump passageways and a transfer valve arrangement in one of said housings, and an outlet passageway and the other of said pump passageways in the other of said housings, which may be disassembled merely by separating said housing sections.

The specification is described with reference to the drawings, in which

Figure 1 is a rear elevational view partly in section of the assembled pumping apparatus.

Figure 2 is a front elevational view partly in section of the assembled pumping apparatus.

Figure 3 is a transverse cross-sectional view in the direction of the arrows 3—3 of Figure 1.

Figure 4 is a plan view partly in section of the upper half only of the pump casing and discharge pipe connections, the section being at the level of the line 4—4 of Figure 1.

Figure 5 is a plan view of the lower half only of the pump housing and inlet pipe connections showing the impellers, impeller shaft and bearing housings in place on the housing.

Figure 6 is a longitudinal cross-section of the pump and housing along the line 6—6 of Figure 5.

Figure 7 is a fragmentary longitudinal section of the volute of the first pump along the line 7—7 of Figure 5.

Figure 8 is a fragmentary longitudinal section of the second volute along the line 8—8 of Figure 5.

Figure 9 is a longitudinal sectional view in the direction of the arrows 9—9 of Figure 3.

Figure 10 is a plan view of the lower half of the pump housing and inlet pipe connection of a modification of the invention.

Figure 11 is a plan view partly in section, of the upper half of the pump housing and outlet discharge pipe of the modified form of the pump shown in Figure 10.

Figure 12 is a longitudinal section through the volute of the first pumping stage of the pump shown in Figures 10 and 11, along the line 12—12 of Figure 11.

Figure 13 is a longitudinal section through the volute of the second pumping stage, along the line 13—13 of Figure 11.

Figure 14 is a longitudinal section through the center discharge passageway along the line 14-14 of Figure 11.

Figure 15 is a fragmentary view of a modified form of lower pump body for use in the pump mechanism shown in Figures 1 through 9.

Figure 16 is a fragmentary side elevation partly in section of the modified form of lower pump body shown in Figure 15.

10 The pumping arrangement shown in Figures 1 through 9 inclusive consists generally of a lower unit generally designated 10, which forms the lower pump body and inlet water connection, and an upper unit generally designated 80, which 15 forms the pump body and outlet water connection.

The lower unit 10 of the pump is preferably a casting as shown in Figures 1, 2 and 5 and is formed with a transverse water inlet passage, 20 generally designated 11. By referring to the left-hand portion of Figure 5 it will be seen that this passage begins at portion 12 and then is divided by web 15 into branches 14 and 16. Branch 14 continues unobstructedly to the inlet chamber 45 of the first pumping stage, and thence to the right-hand end portion 13. Branch 16 runs somewhat parallel to 14 but includes two valves.

At the right-hand end of passage 16, as shown in Figure 5, there is positioned a check valve generally designated 20 which is shown in cross-section in Figure 1. The valve 20 consists of a member 21 which has a through passage 22, and a valve face 23 upon which a valve flap 24 operates. The flap 24 is pivoted in the member 21 and as shown in Figure 1, is oriented so as to prevent flow of water in the direction of arrow 25. The entire valve body 21 is made cylindrical on its outer surface and is positioned in a cylindrical opening 26 in the lower pump unit casting 10, as shown in Figure 5. The opening 26 is covered and the valve body 21 is held in place by a cover plate 28 which is fastened to the lower pump unit casting by a plurality of cap screws 29. The check valve cage 20 being cylindrical may be 45 rotated in its seat to close passageway 13 in the event of failure of the valve flap 24. Thus during operation of the apparatus if valve flap 24 should fail, the entire cage 20 may be rotated 90 degrees and passageway 13 thus closed off. This closure 50 does not preclude the operation of the pump since water may enter the inlet portion 46 by way of channel 12 and passageway 16 through valve 31.

A second cylindrical valve-receiving bore is provided in the lower pump unit at 30 and receives a cylindrical transfer valve generally designated 31. By referring to Figure 2 in which this valve is shown in section, it will be seen that this valve consists of a cage 32 which is formed integrally with a plate 33. The plate 33 serves to 55 close the lower end of the bore 30 in the housing, and the cage 32, which is apertured, receives the rotatable element of the valve.

Within cage 32 there is pivotally mounted a valve body 35 having a plurality of passageways 60 36 and 37 therethrough, as shown in Figure 5. The valve body is provided with a lower stub shaft 39 which is fitted into a bearing socket in the lower plate portion 33, and with an upwardly extended shaft 40 upon which an operating gear 41 is mounted. The shaft 40 protrudes through a portion 44 of the upper pump housing casting which serves to close the upper opening of bore 30 in the lower pump housing casting.

When the transfer valve generally designated 65 31 is in the position shown by the dotted lines of

Figure 5, the passageways 16 of the lower pump unit 10 communicate with passage 36 of the valve 31, and through it, directly with the inlet chamber 46 of the second pump stage. Thus when valve body 35 is positioned with the passage 36, 5 as shown in Figure 5, water may flow from passageway 12 in the direction of arrow 49, through passageway 36 and into chamber 46. Water may likewise flow in the direction of arrow 50 from passage 13 through check valve 20 into the inlet 10 chamber 46.

The passageway from 12 through 14 to chamber 45 and from 13 through 14 to chamber 45 is always open and water may therefore flow therethrough unrestrictedly either in the direction of arrow 51 or in the direction of arrow 52.

The lower pump unit 10 is also provided with a passageway 55 extending from the outlet of volute 66-67 of the first pump stage, which discharges downwardly into the lower housing as shown in 20 Figure 7, to the passageway 31 of transfer valve 31, and thence, as shown in Figure 6, through another passageway 56 in the lower unit 10. Passageway 56 extends from the transfer valve 31 under the pump shaft center bearing 210 and 25 upwardly through opening 58 (see Figures 4, 5 and 6) and then through discharge passageway 59 directly to the discharge pipe 100 of the upper pump unit 80.

The upper unit 80 of the pump body is provided with a portion 69 of the volute of the second pumping stage, which is continued around at 10 in the lower unit 10, and then through opening 71, 30 through passage 72 in the lower pump body and into discharge pipe 100, all as shown in Figure 8. 35

The lower pump unit 10 and inlet pipe casting is provided with a plurality of integrally formed bed plates 61 and 62 which are spaced apart so as to be adaptable to standard frame widths of automotive vehicles, as illustrated in Figure 1 40 and 45 wherein the frame of the automotive vehicle upon which the pump is mounted is shown in section at 63 and 64.

As just explained the upper pump body generally designated 80 comprises passageways which 45 cooperate with those in the lower pump body to form the volutes of the first and second stages of the pump and with a discharge passageway 100 which is positioned so as to be directly above and generally parallel to the inlet passageway 11 of 50 the lower pump body 10. The upper pump body 80 is also provided with a portion 44 which extends to the right, as shown in Figure 2, so as to overlie and form a cover for the cylindrical transfer valve opening 30 in the lower pump body 10. 55 The upper and lower pump bodies when bolted together by bolts 9 form a unitary structure which may be positioned with the inlet and outlet passageways arranged transversely on an automotive chassis.

The outer passageways 12 and 13 of the inlets of the lower pump body 10 are provided respectively with inlet connections 75 and 76 which are closed at the ends with easily removable screw caps 1.

The outer ends of the discharge pipe 100 are flanged as shown at 102 and each end is provided with a check valve mechanism generally designated 103. The check valve 103 comprises a removable plate 104 which forms a valve seat and a 70 member 105 upon which there is pivotally suspended a check valve element 106. The member 105 and plate 104 are bolted to the flange 102 by bolts not shown, as shown in section in Figure 2. When water is forced outwardly in the direc- 75

tion of arrows 107, the check valve element 106 is swung upwardly out of the path of the flow. However, when the pump is not in operation the check valve elements 106 fall downwardly under their own weight into contact with the plate valve seat 104 and a vacuum may thus be drawn in the discharge pipe 100 and in the pump passageways for priming purposes, as will be explained in greater detail hereinafter.

10 The outer portion of member 105 is formed with a flange 110 to which is bolted a cutoff valve 111 which may be of any suitable construction. A valve is provided at each discharge end of pipe 100 so that the flow from the pump may be directed in one or the other, or both directions, and the flow in either direction shut off at will by means of the valve.

15 By referring to Figure 3 it will be noted that the lower unit 10 of the pump body is provided with a web portion 115 at one side and with a second web portion 116 at the other side of the pump. These webs terminate in face plates 117 and 118. Web 117 receives a bearing structure as shown at the left side of Figure 3 and generally designated 120. Web 118 receives gear housing, generally designated 150, and bearing structure generally designated 121 shown at the right side of Figure 3.

20 The bearing structure generally shown at 120 comprises a barrel 122 having a flange 123 throughout a portion of its circumference, as shown in Figure 2. The flange 123 is attached to the face plate 117 by a plurality of bolts 124. The barrel portion 122 is provided with a ball bearing 125, an end cap 126 and a grease seal 127. The bearing 125 is thus enclosed in a grease-tight housing. The portion 128 of the barrel which extends toward the pump body is internally threaded to receive a gland collar 130. 25 Collar 130 is threaded at 131 and provided with a gear portion at 132. In web 115 there is mounted a shaft 133 which carries a worm gear 134 which cooperates with the gear portion 132 of the gland nut and as the shaft 133 is rotated gland 130 is likewise rotated, and due to the threaded connection at 131 the gland is moved longitudinally on the pump shaft. In this way it is possible to vary the pressure upon the packing 135.

30 At the opposite end of the pump shaft 140 there is provided a somewhat similar housing generally designated 121 which in this instance has an extended barrel portion 141 which passes through the gear housing 150. The barrel 141 supports two ball bearings 142 and 143 on shaft 140. The barrel 141 is provided with a grease-retaining ring 144 and with a grease-tight cover plate 145 which is attached to the structure by means of bolts 146, and is also provided with a gland nut arranged similarly to that described above with reference to the barrel 120, which serves to regulate the pressure on packing 147.

35 The gear housing generally designated 150, which is mounted between the face plate 118 of the pump structure and the flange 148 of bearing housing 121 is provided with a shaft 151 which is fitted for connection in the drive shaft line of the automotive vehicle upon which the pumping unit is mounted. The shaft 151 is carried by bearing 152 and by a pilot bearing 153 which is carried in the end of a second shaft 154, also mounted in the housing on a pair of ball bearings 155. The shaft 151 is provided with a splined portion 156 upon which there is slidably mounted a correspondingly internally splined

shift gear 157 which is arranged to be moved from the position shown in Figure 3 to any of the dotted line positions 158, 159 or 160 by means of a shift fork, a portion of which is indicated at 163. The shifting fork is arranged to be operated by a gear shift unit 164 shown in Figure 1 as being mounted at one side of the gearing housing 150. Shafts 151 and 154 are provided with suitable grease seals at 168 and 169 respectively.

10 The housing 150 is also provided with an idler gear 170 which is mounted by means of ball bearings 171 upon a fixed shaft 172. As shown in Figure 9, the gear 170 is of such a diameter that it meshes with a gear 175 which is mounted between bearings 142 and 143 upon the pump shaft 140. Thus when gear 157 is in the position shown by the full lines in Figure 3 power from shaft 151 will be transmitted through gears 157 and 170 to gear 175, and the pump shaft 140 will accordingly be rotated.

15 The housing 150 is also provided with another idler gear pair 180 which is composed of an integrally formed unit of two gears of slightly different diameters. This gear pair is mounted below and to one side of gear 157 as shown in Figures 2 and 9. One of the gears of the pair meshes with slide gear 157 (when the latter is in position 158, Figure 3), and another of the gears of the pair meshes with a gear 181 (see Figures 2 and 9) on the drive shaft of the priming pump, generally designated 185.

20 The priming pump consists of a casing 186 in which there is mounted a pair of intermeshing pump gears 187 and 188 which are fitted so as to rotate in contact with the interior of casing 186 as is well known in the art. The housing 186 is provided with an end plate 190 which is attached to the priming pump housing by means of screws 191.

25 The priming pump 185 is provided with an inlet connection 194 which communicates with the main pump outlet pipe 100 (see Figure 6) at flange 195 as shown in Figure 2.

30 The gear pair 180 is positioned in the housing 150 so as to be engaged by gear 157 when in the position 158, but to be out of engagement with gear 157 when the latter is moved to position 159. It will be noted that in position 159 gear 157 is just out of contact with gear 198 which is carried by shaft 154. When gear 157 is in the position 160 gear 198 fits neatly into the internal splines 199 of gear 157 so that power will be transmitted from shaft 151 to 154.

35 The gearing arrangement in casing 150 thus has four operating positions. First, when the gear is in the position shown by the full lines in Figure 3, power will, as previously explained, be transmitted from the shaft 151 to the main pump shaft 140. Second, when the gear 157 is in the position 158, power will be transmitted from shaft 151 through gear pair 180 to the priming pump generally designated 185. Third, when the gear 157 is in the position 159, shaft 156 is disconnected from both the priming pump and the main pump and also from the automotive drive shaft 154, or is "in neutral." Fourth, when the gear 157 is in the position 160 power will be transmitted from shaft 151 to the drive shaft 154 of the automotive vehicle.

40 The main pump body, as previously explained, is divided into a lower casting generally designated 10, and an upper casting generally designated 80. However, certain of the pump parts are integral throughout their upper and lower

portions. Thus there are provided nosings 200 and 201 which surround the shaft 140 and are adapted to be carried by the split upper and lower housings. Similarly the wear rings 202, 204, 206 and 208 are integral throughout their circumference as is also the center bearing structure which consists of a center housing block 210 and insert 211. The block 210 is provided with passageways 212 into which grease may be forced after pumping water through a connection not shown. In assembling the pump structure the nosings 200 and 201 are fitted onto the shaft along with the impellers 215 and 216, the center housing core 210-211 and rings 202, 204, 206 and 208. The housing is then closed and the center housing core rings and nosings are supported so that slight clearances are maintained between the stationary nosings and the rotatable shaft 140 and between the stationary rings 202, 204, 206 and 208 and the rotatable impellers 215 and 216 adjacent them. This construction is desirable for simplicity of manufacture, ruggedness and ease of assembly.

After the pump structure shown in Figures 1 through 9 has been mounted on an automotive vehicle and the necessary mechanical connection made between the drive shaft of the vehicle and the shaft 151, the pump may be placed in operation as follows:

Either or both of the caps 17 are removed and inlet hose connections are made to a source of water, such as a fire hydrant, or to a reservoir. Outlet hoses are then connected to one or both of the valves 111. During idle periods the pump is always maintained dry so as to preclude damage due for instance to freezing conditions, and it is therefore necessary to prime the main pump. When water under pressure is available as at a fire hydrant, water is forced to the pump but when a reservoir or other source is used the pump must be primed as follows: Gear shift mechanism 164 is manipulated, first to move the gear 157 out of engagement with gear 198 and into engagement with the gear pair 180 of the priming pump. The engine of the automotive vehicle is then speeded up and the priming pump draws air out of the discharge pipe 100 of the main pump and through the communicating pump passageways back to the intake. At this time check valves 106 are both closed as shown in Figure 2, and air is thus prevented from entering the main discharge pipe 100 from the hose line or lines which may be attached to the valves 111. The vacuum is thus drawn in the main pump discharge and communicating passageways through the passageways to the inlets 12-13 through inlet connections 75-76 and to the supply hose, and water is accordingly elevated from the reservoir and the pump is filled. The automotive engine is then idled and gear 157 is moved from the position 158 in which it was in operating connection with gear pair 180 to the position shown in Figure 3. During this time the water which has been drawn into the pump passageways and discharge pipe 100 is maintained in place due to the action of check valves 103 which served to hold the vacuum produced in the system by priming pump 185. After the gear 157 has been shifted to the position shown in Figure 3 the automotive engine is again accelerated and impellers 215 and 216 are there- 70 after effective to draw water through the inlet passageway 12-13 into the pump and discharge the water into the outlet passageway 100. The flow of water thus produced lifts the valve flaps 106 and the water is discharged through gate 75 valves 111 to the discharge hoses.

For parallel operation the transfer valve is rotated by means of hand-wheel 224 which operates through gears 220 and 41 (see Figures 1 and 2) until the valve passageways 36 and 37 are in the positions shown by the dotted lines of Figure 5. In this position passageway 36 connects the passage 16 and inlet chamber 46 (see Figure 5) and passage 37 connects passage 55 with passage 56 (see Figures 5 and 6). The inlet supply is then by way of passageway 12 and 10 water may flow directly along the path of arrow 51 to the inlet chamber 45 of the first pump stage and may also flow in the direction of arrow 49 to the inlet chamber 46 of the second pump stage. If the inlet supply should be through passageway 13 water may flow directly in the direction of arrow 52 to chamber 45 of the first pump stage and through the check valve generally designated 20 and in the direction of arrow 50 to chamber 46 of the second pump stage.

Under these conditions the discharge from the volute 66-67 of the first pumping stage is by way of passageway 55, passage 31 in the transfer valve 31, thence through passage 56, as shown in Figure 6, through 58, and thence directly through passage 59 to the discharge pipe 100 in the upper pump body 80. At the same time discharge from the volute 69-70 of the second stage (see Figures 5 and 8) is directly upward through opening 71 and through passage 72 to the discharge pipe 100. Thus with the transfer valve 31 in the position shown by the dotted lines in Figure 5 the first and second pumping stages operate in parallel and the pump mechanism delivers a maximum of water at a predetermined pressure.

For series operation the transfer valve 31 is again shifted by means of hand-wheel 224 until passages 36 and 37 are moved to the positions shown by the dot-dash lines of Figure 5. Passage 36 in the transfer valve cylinder will then communicate from the discharge 55 of the first pumping stage to the inlet chamber 46 of the second pumping stage. At this time the short curved passage 37 of the transfer valve is idle. The transfer valve in this latter position thus has the effect first, of blocking the flow from the inlet 12 in the direction of arrow 49 directly to the inlet chamber 46 of the second pumping stage, and second, of interrupting the flow from the discharge passage 55 through the passage 56 of the lower 50 pump body through opening 58 and passage 59 (Figures 10 and 11) to the main discharge pipe 100. Under these conditions series operation of the pump ensues as follows:

Water is drawn into the chamber 45 of the first pumping stage either in the direction of arrow 51 from inlet passage 12 or in the direction of arrow 52 from inlet passage 13, depending upon to which side of the machine the inlet hose is connected. The flow then proceeds through chamber 45 through the impeller 216 to the volute 66-67 (see Figure 7) of the first stage, thence through passageway 55 in the lower pump body through transfer valve passage 36 (which is in the position shown by the dot-dash lines of Figure 5) and thence to the inlet chamber 46 of the second pumping stage. From this point the water is delivered by impeller 215 to the volute 69-70 (see Figure 8) of the second pumping stage and thence directly upwardly through opening 71 and passage 72 to the main outlet pipe 100. Under these conditions the pumping apparatus delivers a maximum pressure with a comparatively smaller flow. At this time also it will be noted that pressure is de- 78

veloped in passageway 16 between the transfer valve 35 and the suction check valve 20 (see Figure 5), and as a result the gate 24 of the check valve 20 is forced shut against the valve face 23 with the result that back flow into the inlet passage 13 from the inlet of the second stage is prevented.

Whenever desired, the transfer valve 31 may be changed from the position in which the pumping stages operate in parallel to the position in which they operate in series, merely by rotating gear 41 (see Figure 2) by means of worm gear 220 which is mounted upon shaft 221 (see Figure 1). The shaft 221 is pivotally mounted in upstanding lugs 222, formed as an integral portion of the upper pump body 80. Shaft 221 is also provided with an extended portion 223 and a hand wheel 224 so that it may be operated conveniently from one side of the automotive vehicle.

In the device shown in Figures 1 through 9 water from inlet port 13 may reach the inlet chamber 46 of the second pumping stage through the check valve generally designated 20 and passage 16, and to a limited extent flow may occur from 13 along arrow 52 to and through the inlet chamber 45 of the first pump stage then through 14 oppositely to arrow 51 around the end of web 15 then in the direction of arrow 49 through 16 and 36 again to the inlet chamber 46. However this flow is negligible due to the shaping, the passageways and the tortuousness of the path. In the modification shown in Figures 11 through 13 this path has been eased by adequately sizing the passage 14 to accommodate the flow to both pump stages and by omitting sharp bends. As a consequence flow to the second pumping stage is provided only through the transfer valve 31 and the branch 16 and check valve 20 of the first modification (see Figure 5) are accordingly omitted.

By referring to Figure 10 it will be seen that flow through the main inlet passageway 11 of this modification is facilitated by the size of passage 10 which is positioned directly below the inlet chamber 45 of the first pumping stage with which it communicates. Thus flow may take place in the direction of arrow 52 directly to chamber 45 of the first pumping stage and a portion of the flow may continue in the direction of arrow 50 through passageway 36 of the transfer valve 31, to the inlet chamber 46 of the second pumping stage. It will be recalled that in the first modification the flow 50 was directly from the inlet passage 13 through the check valve 20 to the inlet chamber 46 but in the second modification the inlet flow to the chamber 46 is first taken transversely of the pump and thence around through the transfer valve to the inlet chamber 46. This modification of the invention is otherwise similar to the first modification, shown in Figures 1 through 9, except for slightly different shaping of passageway 100, as shown in Figure 11 and of the transfer passage 56 from the transfer valve 31 through opening 58 and passage 59 to the discharge pipe 100, as will be seen by comparing Figure 14 and Figure 6. In Figure 14 the center bearing portion is of reduced diameter as compared with that shown in Figure 6.

In both of the modifications the transfer passage 56 and the transfer valve 31 are located in the lower half of the pump body. By thus locating those elements of the mechanism we have been able to achieve a much smaller over-

all height of the pump mechanism and a much more compact and easily accessible pump than in previous mechanisms of this type.

In Figures 15 and 16 there is illustrated a modified form of lower unit for use in the pump shown in Figures 1 through 9. In this modification the web 250 which divides passages 14 and 16 is extended out to the flange end of inlet 13 and the check valve is likewise moved out to the new position as shown at 251. The inlet gooseneck pipe 252 is provided with a web 253 which terminates in a valve seat portion 254 against which valve 251 seats. The valve 251 is pivoted upon pintle 255 which is in turn supported from the gooseneck inlet casting 252.

It is obvious that many modifications may be made without departing from the spirit of the invention herein described and claimed as follows:

We claim:

1. A two-stage centrifugal pump comprising a rotary member having first and second stage impellers in spaced relation thereon, an axially divided housing having upper and lower sections, said housing being formed with an inlet to each impeller in said lower section, and with first and second volutes part in each section for the first and second impellers respectively, including an outlet passageway in the upper section communicating directly with the second volute, a discharge connection from the first volute to said outlet passageway, said discharge connection being located between the volutes in said lower section, a second inlet to the second impeller, said inlet also being in the lower section, and valve means in said lower section for transferring the flow from the first volute into the discharge connection or into said second inlet connection.

2. A two-stage centrifugal pump comprising a rotary member having a first and second impeller in spaced relation thereon, a housing for said rotary member and impellers, said housing being divided axially into upper and lower sections and including intakes and spaced first and second volutes for said spaced first and second impellers, respectively, a discharge passage for parallel operation of said impellers, said passage being in the lower housing section between the spaced volutes and beneath said rotary member, an outlet pipe formed on said upper housing section communicating directly with the second volute and with said discharge passage of the lower housing, a second passage in said lower housing section for series operation of said impellers, said second passage communicating with the intake of the second impeller, and valve means in the lower housing for selectively directing the flow from said first volute to the said discharge passage or to said second passage.

3. A multiple stage centrifugal pump system adapted for mounting upon an automotive chassis for fire engine service, comprising an open-ended water inlet manifold, an open-ended water outlet manifold of a length substantially corresponding to that of the inlet manifold arranged substantially parallel with and above the outlet manifold, a pump shaft having primary and secondary impellers in spaced relation thereon mounted between said manifolds and in a plane which is substantially at right angles to the manifolds, a pump housing including an intake and discharge volute for each impeller arranged between said manifolds, said housing being divided into upper and lower portions along a plane passing through the said pump shaft, the lower housing being

- formed with a direct passageway between the intake manifold and the intake of the primary impeller, and with a first and second branch passageway from the intake manifold to the intake 5 of the secondary impeller, a check valve in the first said branch passageway, said lower housing also being formed with a transfer passage from the discharge volute of the first impeller to the second branch passageway and a transfer valve located in the lower housing for closing the 10 second branch passage from the intake manifold to the secondary impeller and for directing the flow from the discharge volute of said primary impeller to the branch passage of the secondary 15 impeller.
- 15 4. A multiple stage centrifugal pump system adapted for mounting upon an automotive chassis for fire engine service, comprising an open-ended water inlet manifold, an open-ended water outlet manifold of a length corresponding to that of the inlet manifold, arranged substantially parallel with and above the outlet manifold, a pump shaft having first and second impellers in spaced relation thereon mounted between said manifolds and in a plane which is substantially at right angles to the manifolds, a pump housing including an intake and a discharge volute for each impeller arranged between said manifolds, said housing being divided into upper and lower portions along a plane passing through the said pump shaft, the lower housing being formed with a direct passageway between the intake 20 manifold and the intake of the primary impeller, a branch passageway from the intake manifold to the intake of the secondary impeller, said lower housing also being formed with a transfer passage from the discharge volute of the first 25 impeller to the branch passageway and a transfer valve located in the lower housing for closing the branch passage from the intake manifold to the secondary impeller and for directing the flow from the discharge volute of the said primary impeller to said branch passage of the secondary impeller.
- 30 5. A multiple stage centrifugal pump system adapted for mounting upon an automotive chassis for fire engine service, comprising an open-ended water inlet manifold, an open-ended water outlet manifold of a length substantially corresponding to that of the inlet manifold arranged substantially parallel with and above the outlet manifold, a pump shaft having primary and secondary impellers in spaced relation thereon mounted between said manifolds and in a plane which is substantially at right angles to the manifolds, a pump housing including an intake and discharge 35 volute for each impeller arranged between said manifolds, said housing being divided into upper and lower portions along a plane passing through the said pump shaft, the lower housing being formed with a direct passageway between the intake manifold and the intake of one of the first impeller and with a discharge passage from that impeller to said outlet manifold, said lower housing also being formed with a branch passageway from the intake manifold to the intake of the second impeller, and a manually controlled valve in said lower housing for simultaneously controlling flow 40 in said discharge and branch passageway, said valve in one position directing flow from the first impeller through said discharge passage to the outlet manifold and from the inlet manifold through the branch passageway to the second impeller, and in another position directing flow 45 from the first impeller through said branch passageway to the second impeller and interrupting the flow from the intake manifold through said branch passageway to the second impeller.
- 50 6. A two-stage centrifugal pump system adapted for mounting upon an automotive chassis for fire engine service comprising an open-ended water inlet manifold and support, an open-ended water outlet manifold of a length corresponding to said inlet manifold length and arranged substantially parallel with and above the outlet manifold, a pump rotor having first and second impellers thereon arranged between the manifolds and at an angle thereto, a housing including an inlet for the impellers and with downwardly and upwardly discharging volutes for the first and second impellers respectively, said housing being divided into upper and lower sections, and passageway means and transfer valve means 55 in said lower section for in one condition directing flow from the downwardly discharging volute of the first impeller to the outlet manifold and for directing fluid inflow from the inlet manifold to the inlet of the second impeller, and in another

condition for interrupting such inflow and for transferring the flow from the first impeller volute to the intake of the second impeller.

6. A multiple stage centrifugal pump system adapted for mounting upon an automotive chassis 5 for fire engine service, comprising an open-ended water inlet manifold, an open-ended water outlet manifold of a length substantially corresponding to that of the inlet manifold arranged substantially parallel with and above the outlet manifold, a pump shaft having primary and secondary impellers in spaced relation thereon mounted between said manifolds and in a plane which is substantially at right angles to the manifolds, a pump housing including an intake and discharge volute 10 for each impeller arranged between said manifolds, said housing being divided into upper and lower portions along a plane passing through the said pump shaft, the lower housing being formed with a direct passageway between the intake manifold and the intake of the primary impeller, a branch passageway from the intake manifold to the intake of the secondary impeller, said lower housing also being formed with a transfer passage from the discharge volute of the first 15 impeller to the branch passageway and a transfer valve located in the lower housing for closing the branch passage from the intake manifold to the secondary impeller and for directing the flow from the discharge volute of the said primary impeller to said branch passage of the secondary impeller.

7. A multiple stage centrifugal pump system adapted for mounting upon an automotive chassis 35 for fire engine service, comprising an open-ended water inlet manifold, an open-ended water outlet manifold of a length substantially corresponding to that of the inlet manifold arranged substantially parallel with and above the outlet manifold, a pump shaft having primary and secondary impellers in spaced relation thereon mounted between said manifolds and in a plane which is substantially at right angles to the manifolds, a pump housing including an intake and discharge volute for each impeller arranged between said manifolds, said housing being divided into upper and lower portions along a plane passing through the said pump shaft, the lower housing being formed with a direct passageway between the intake manifold and the intake of the primary impeller and with first and second branch passageways from the intake manifold to the intake of the secondary impeller, a check valve in the first said branch passageway, said lower housing also being formed with a transfer passage from the discharge volute of the first impeller to the second branch passageway and a transfer valve located in the lower housing for closing the second branch passageway from the intake manifold and the secondary impeller and for directing the flow from the discharge volute of said primary impeller to the branch passage of the secondary impeller, said check valve being carried by a cylindrical valve cage positioned transversely of said first branch passageway, said cage being rotatable to close off said passageway in the event of failure of the check valve.

RALPH R. BOYLES.
